(57) **CLAIM**

The ornamental design for an integrated control valve, as shown and described.

DESCRIPTION

FIG. 1 is a perspective view of an integrated control valve showing the inventive design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a detail view of the region indicated in FIG. 2.

The broken lines shown in the figures are for the purpose of illustrating portions of the integrated control valve and form no part of the claimed design.
